UNITED STATES PATENT OFFICE.

GEORGE WORDINGHAM, OF MILWAUKEE, WISCONSIN.

SHIRT-WAIST HANGER.

Specification of Letters Patent. Patented Apr. 18, 1916.

1,179,596.

Application filed March 23, 1915. Serial No. 16,382.

To all whom it may concern:

Be it known that I, GEORGE WORDINGHAM, a citizen of the United States, residing at Milwaukee, in the county of Milwaukee and State of Wisconsin, have invented certain new and useful Improvements in Shirt-Waist Hangers, of which the following is a specification.

My invention relates to garment forms and has for its object the provision, as a new article of manufacture, of a shirt waist form which may be employed by both manufacturers and dealers of such garments or by laundries; as hangers for waists in the laundry and as forms for preventing crumpling of the waist when packaged for return to the owners. In any event, I provide a form adapted to be arranged within a shirt waist in such a manner as to prevent rumpling or creasing of the waist, if wrapped in a bundle or to afford protection to the waist if placed in an ordinary box.

A still further object of my invention is the provision of a shirt waist form so constructed that, in use, it will serve to support the collar, shoulder and bosom portions of the waist to effectually and artistically display any embroidery or lace-work thereon, for which reason the form is particularly adapted for use as a hanger for waists, as well as a protection for waists when being packed or shipped.

A further object of my invention is to provide a garment form of the above type which will be constructed from a single blank of cardboard or other suitable material adapted to be shipped and stored in flat form and to be assembled or set up only when it is to be used.

A still further object of my invention consists in so constructing the waist form that there will be no loss of material in stamping out the blanks from which the form is made, but one stamping process being required.

A still further object of my invention consists in so constructing the form that it will offer the maximum resistance to distortion in use and at the same time be capable of being readily set up. In this connection, I construct the form constituting blank in such a manner that it may be set up by the use of one hand only and in a rapid and convenient manner.

With these and other objects in view, my invention will be more fully described, illustrated in the accompanying drawings, and

then specifically pointed out in the claims which are attached to and form a part of this application.

In the drawings: Figure 1 is a perspective view, illustrating the form embodying my present invention, a waist being arranged thereon; Fig. 2 is a perspective view of the form in condition for use; Fig. 3 is a fragmentary plan view of the blank in its initial condition, only the upper portion of the blank being shown.

Corresponding and like parts are referred to in the following description and indicated in all the views of the drawings by the same reference characters.

My improved garment form is constructed from a single blank of cardboard or other suitable, relatively stiff material, the blank being rectangular in shape and of a size suitable for the garment which it is to support. In Fig. 3, such blank is indicated by the numeral 10 and the various incisions made in the blank to adapt it for use in the garment form are clearly shown. The blank is provided medially of its width and slightly spaced from one end with a transverse incision 11 parallel with such end and having curved portions 12 directed toward the opposite end of the blank. Parallel incisions 13 form continuations of the incision 11, extending longitudinally of the blank and consequently parallel with its sides, the three incisions thus formed defining a tongue 14. An opening 15 is formed in the free end 90 portion of this tongue, that is, near the transverse incision 11.

Somewhat below the lower ends of the incisions 13, the blank is formed with a further transverse incision 16 having downwardly curved portions 17, from which extend the parallel longitudinal incisions 18, these incisions being in line with the corresponding incisions 13, thereby defining a second flap or tongue 19 in longitudinal alignment with the first and spaced slightly below it. Relatively short transverse incisions 20 extend inwardly from the intermediate portions of the incisions 18 and in transverse alignment with each other, the inner ends of these incisions being spaced whereby the end portion of the tongue 19 is provided with locking flaps 21, the purpose of which will be later explained. At this point I wish to point out that none of the incisions thus formed extend through the edges of the blank and there is, therefore,

very little likelihood of the blank being torn during handling. The blank, in the condition just described, is adapted to be packed in large numbers in flat condition, 5 for shipment or storage and is not intended to be set up until ready for use.

When it is desired to use the form, that end portion of the blank, from which the tongues 14 and 19 are struck, is bent forwardly and its free edge is inserted behind the tongue 19 which is sprung forwardly somewhat, as shown in Fig. 2, for this purpose. At the same time that the tongue 19 is sprung forwardly to receive the edge of the blank, the flaps 21 carried by the tongue are sprung rearwardly through the opening defined by the tongue 14 to engage against what is now the rear face of the turned over portion of the blank, at either side of the opening from which the tongue 14 was formed, the curved portions 12, formed by the meeting ends of the incisions 13 and incision 11, seating in the incisions 20 of the tongue 21. Under these conditions, two shoulder rolls 22 are formed, one at either side of the tongue 14 which serve to effectually support the collar, shoulder and bosom portions of the waist when the garment is positioned upon the form in the manner shown in Fig. 1. It should be noted that these shoulder rolls or shoulder form portions of the garment form are connected and therefore one serves to support the other. It should further be noted that because of this connection, both rolls are formed in a single operation. Due to the fact that the free end edge of the blank seats in the lower ends of the incisions 18, the tongue 19 serves to absolutely hold the shoulder rolls against further bending or rolling movement, while the locking engagement of the flaps 21, in the inner ends of the rolls, prevents straightening out of the rolls.

The form above described may be readily set up with one hand, if desired, but may most conveniently be set up by grasping one edge of the blank, adjacent the end having the tongues, with one hand, while springing out the tongue 19 with one finger of the other hand and at the same time springing back the flaps 21 with the other fingers of the same hand manipulating the tongue 19. The upper end of the blank 55 may then be swung into position behind the tongue 19, the flaps 21 passing readily through the opening defined by cutting out the tongue 14 and being then released to spring into place and lock the form in 60 assembled or set up position.

From the foregoing description of my invention, it will be seen that I have provided a garment form blank, large numbers of which may be packed in a minimum space 65 and so constructed as to be little liable to

injury in handling or shipment. It will further be clear that the form may be readily set up, when required, for use, and a waist readily and quickly fitted thereon and properly supported against creasing or 70 rumpling.

The tongue 14 forms a hanger, permitting the suspension of garments in a closet or like place upon the forms upon which they are positioned when returned from the laundry, thereby avoiding the likelihood of 75 rumpling or soiling the garments by the necessity of removing such forms as are now commonly in use and replacing them with the ordinary garment hangers commonly used. This tongue also prevents lateral disarrangement of the garment upon the form, although it may, if the form is to be packed in a box, have its free end bent downwardly and engaged behind the tongue 85 20 in order to shorten the package.

Having thus described the invention, what is claimed as new is:

1. A garment form including a relatively flat body formed from a blank having parallel longitudinal incisions connected near one end by a transverse incision forming a tongue, such end of the body being bent over and secured to the body, whereby the tongue forms a suspension means and the bent over portions provide shoulder form portions at either side of the suspension means, the body being further provided with a second tongue insertible in the opening formed by the first tongue when the end is turned over and 100 adapted to retain the bent over portions against the body portions.

2. A garment form including a relatively flat body formed from a blank having parallel longitudinal incisions connected near one end by a transverse incision forming a tongue, such end of the body being bent over and secured to the body, whereby the tongue forms a suspension means and the bent over portions provide shoulder form portions at either side of the suspension means, the body being further provided with a second tongue insertible in the opening formed by the first tongue when the end is turned over, 110 said second tongue having lateral flaps for 115 locking engagement with the turned over portion of the body.

3. As a new article of manufacture, a blank for a garment form provided adjacent one end with a medial transverse incision and with spaced longitudinal incisions forming continuations of the transverse incision to define a tongue, which tongue is provided with an opening in its free end, the blank in longitudinal spaced relation to the first tongue being provided with a second transverse incision and with spaced longitudinal incisions in alignment with the former longitudinal incisions to provide a second tongue.

4. As a new article of manufacture, a blank for a garment form provided adjacent one end with a medial transverse incision and with spaced longitudinal incisions forming continuations of the transverse incision to define a tongue, which tongue is provided with an opening in its free end, the blank in longitudinal spaced relation to the first tongue being provided with a second transverse incision and with spaced longitudinal incisions in alignment with the former longitudinal incisions to provide a second tongue, said second tongue being formed intermediate its length with inwardly extending transverse incisions to define lateral flaps.

5. A garment form including a relatively flat body having one end portion rolled back upon itself, an upstanding tongue being struck out from the rolled portion but leaving the end of such rolled portion continuous, and a second tongue struck out from the body and bent forwardly to receive behind it the continuous edge of the rolled portion, the second tongue being in alignment with the first and formed with lateral locking flaps insertible through the opening formed in the rolled portion by striking out the first tongue to lock the rolled portion against return movement.

the opening formed by the first for locking engagement with the continuous rolled portion of the form.

6. A garment form including a relatively flat body having one end portion rolled back upon itself, an upstanding tongue being struck out from the rolled portion but leaving the end of such rolled portion continuous, and a second tongue struck out from the body and bent forwardly to receive behind it the continuous edge of the rolled portion, the second tongue being in alignment with the first and formed with lateral locking flaps insertible through the opening formed in the rolled portion by striking out the first tongue to lock the rolled portion against return movement. 40

In testimony whereof I affix my signature in presence of two witnesses.
